Specification for Design.

Patented Oct. 31, 1916.

Application filed September 18, 1916. Serial No. 120,806. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Bracket-Back for Lighting-Fixtures, of which the following is the specification, reference being had to the accompanying drawing, forming part thereof.

Figure 1 is a front view of a bracket back for lighting fixture, showing my new design. Fig. 2 is a side view of the same.

I claim:

The ornamental design for a bracket back for lighting fixture, as shown.

LESTER R. WELLMAN.
